UNITED STATES PATENT OFFICE.

JOHN CLIFFORD YORDON, OF QUEENS VILLAGE, NEW YORK, ASSIGNOR TO LAMINATED SHIM COMPANY, INC., OF LONG ISLAND CITY, NEW YORK, A CORPORATION OF NEW YORK.

SHIM.

Original application filed March 19, 1923, Serial No. 625,960. Divided and this application filed July 15, 1924. Serial No. 726,218.

This invention is a division of my application Serial No. 625,960, filed March 19, 1923, and relates to an improvement in shims and more particularly to shims which are used between the parts of a bearing and which can be reduced in thickness by the removal of one or more laminæ without any inconvenience or loosening of the other laminæ of the shim.

10 A particular object, therefore, is to produce a shim which can readily be reduced in thickness, which will act as a take up for wear on the shaft and prevent rattling of the bearing parts and which can be manufactured economically and efficiently.

15 A further object of my invention is to produce a shim, the laminæ of which will hold themselves together without the aid of a binding element such as lead or other malleable metal.

20 Various other objects and advantages will appear as the description of the invention proceeds.

25 Referring now to the drawings which illustrate a preferred form of embodiment of the invention,

Figure 1 is a plan view of a shim embodying my invention.

30 Figure 2 is a sectional view of the same.

35 Figure 3 is a front elevation, partly in section, of a power press showing one method of forming my shim.

40 Figure 4 is a front elevation of a press and shim therein similar to that shown in Figure 3 illustrating a modification in which the edges of the shim material at the bolt hole therein are bent downwardly by a projection on the head of the press.

45 In the embodiment illustrated, the shim comprises a body portion 1, consisting of a plurality of laminæ 2 of thin brass strips or the like, shaped according to the bearing which the shim is to fit and provided with one or more holes 3 therethru for the bolts which hold the parts of the bearing together.

50 Heretofore with shims of this type, it has been customary to provide a binding material such as very soft solder, lead, or other adhesive to hold the separate laminæ together and prevent accidental separation thereof during shipment or when removed from the bearing.

55 In the present invention, however, this is prevented without the use and expense of a

binder by bending the edges of the laminæ over upon each other as shown at 4 under sufficient pressure to cause adhesion of the overlapped portions to hold the laminæ together.

60 Obviously the bending over of the edges of the laminæ could be done in various ways, for example, by hammering the edges on a properly shaped anvil, by using a pair of pliers and a vise, by forming the separate laminæ with a turned or cupped edge and nesting the same together, or in various other ways.

65 However, it is preferred to use the apparatus illustrated in Figures 3 and 4 for this purpose.

70 This apparatus comprises, a press having a platen 5 of slightly smaller size than the shim laminæ 2 which it supports. The platen 5 may be provided with a suitable ledge (not shown) against which one edge of the laminæ may be aligned in properly superposed relation. A head 7 carried for reciprocation by the plunger 8 cooperates with the platen 5 to press the laminæ together and turn down the edges thereof upon each other as indicated at 4, to cause the laminæ to adhere to each other. For this purpose the head 7 is made slightly larger than the platen 5 and is provided with a depending rim 10 which comes down around the platen 80 to press the turned over edges of the laminæ together. The lower edge of the rim 10 is beveled at 11 to permit easy bending of the edges of the shims.

75 In Figure 4 I have added an additional 90 step by providing the press head with a cylindrical projection 13 which overlies the bolt hole 3 in the shim laminæ and whose diameter is slightly greater than the diameter of said hole. Therefore, when the projection passes thru the hole 3 it also will bend the edges of the laminæ around the hole, downwardly with the same effect as that produced by the projections 10 on the head of the press. In order to permit the 95 bending of the edge of the hole 3, I provide a suitable larger diameter of hole or depression 15 in the bed 5 of the press which allows the projection 13 to pass thru the hole 3.

100 The lower surface then of the shim has projecting portions, at its opposite edges and around the hole. This will give the 105

shim a spring like effect when placed between the parts of a bearing, and when the wear occurs on the shaft the shim will tend to keep the parts of the bearing from rattling until the wear is sufficient to make necessary the reduction in thickness of the shim which is accomplished by removing one of the laminae with a knife-edge.

It is to be understood that I am not confined to the use of any particular metal or process in making the shims nor to the particular edges to be bent down.

I claim:—

1. As an improved article of manufacture, a shim comprising a series of superposed sheets each sheet having its edges slightly bent upon the edges of the sheet beneath.
2. As an improved article of manufacture, a shim comprising a series of superposed

sheets each sheet having its edges slightly bent upon the edges of the sheet beneath and held thereagainst by adhesion.

3. As an improved article of manufacture, a shim comprising a plurality of superposed matched sheets having an opening there thru and having the outer edges of the sheets and the edges bordering the opening slightly bent downwardly upon the edges of the sheets beneath and held thereagainst by adhesion.

4. As an improved article of manufacture, a shim, comprising a series of superposed laminae, with turned-down edges, the laminae being held together by the frictional contact of the turned-down edges thereof.

In testimony whereof I have affixed my signature to this specification.

JOHN CLIFFORD YORDON.
